RAILWAY TRAFFIC CONTROLLING
APPARATUS

Ronald A. McCann, Swissvale, Pa., assignor to
The Union Switch & Signal Company, Swiss-
vale, Pa., a corporation of Pennsylvania

Application July 18, 1936, Serial No. 91,256

4 Claims. (Cl. 246—3)

My invention relates to railway traffic controlling apparatus, and more particularly to apparatus for use in connection with centralized traffic controlling systems for railroads. In systems of this character, it is customary to govern the operation of railway signals and switches situated at remote points from a central control point, usually the dispatcher's office, and it frequently occurs that junctions, yards, or the like, at which local switching is to be done and at which local operators are continuously on duty, are situated within the controlled territory. The duties of these operators will ordinarily include the control of the adjacent main line signals, under orders received by telephone or otherwise from the dispatcher. This local control of the signals possesses certain advantages and it is often desirable to retain such control even though a centralized traffic control system has been provided which permits these signals to be controlled from the dispatcher's office without the intervention of the local operators. This is particularly the case when the main line tracks are signaled for either direction of operation.

One object of the present invention is the provision of means whereby the signals governing traffic movements toward or away from such points are controlled jointly by the local operator and by the operator at the distant control office, so that a signal can not be cleared or a given direction of traffic set up by either operator without the knowledge and cooperation of the other.

In the embodiment of my invention herein illustrated, this object is accomplished by the provision of apparatus for controlling the traffic direction which is under the control of the local operator, and by the provision of means for selectively clearing the signal for one direction or the other under the control of the distant operator.

Referring to the accompanying drawing, the reference characters **1** and **1a** designate the track rails of a stretch of railway track over which traffic moves in both directions between the passing tracks at the ends of the stretch. The track rails **1** and **1a** are divided by insulated joints **2** to form track sections each of which is identified by the reference character **T** with a distinguishing prefix, and each track section is provided with the usual track circuit comprising a track battery **3** and a track relay **TR**. Sections **5T** and **7T** include the track switches identified by the references **5** and **7**, respectively, and traffic movements through the switch sections are gov-

erned by the signals bearing the general references **6** and **8**, with identifying prefixes.

Each signal is controlled by a signal relay **H** identified on the drawing by a prefix corresponding to the signal it controls. As hereinafter explained in detail, signal **RA6** or **RB6**, depending upon the position of switch **5**, governs traffic movements from left to right through the single track stretch, its control limits extending to the opposing signal **LA8** or **LB8**, while the latter signals govern traffic movements from right to left in accordance with the position of switch **7**, their control limits extending to signal **RA6** or **RB6**.

It is to be understood that switch **7** is located at the hereinbefore mentioned junction point or yard at which the local operator is stationed. The signals **LA8**, **LB8**, or the opposing signals **R8** may be cleared by that operator by moving a signal lever **G8** from its normal position as shown to position **L** or **R**, respectively. The control of the direction of train movements through the single track stretch is effected by the local operator by the energization of one or the other of a pair of interlocked stick relays **LFS** and **RFS** by the operation of a traffic lever **F** to its position **L** or **R** in accordance with the direction to be established.

The centralized traffic control system may be of any suitable type, and to illustrate the present invention it has been assumed that this is of the time code type such as is disclosed in a copending application for Remote control system, Serial No. 600,786, filed March 23, 1932, by Lloyd V. Lewis. The detailed operation of the system is immaterial as far as the present invention is concerned, and it is deemed sufficient to point out that it includes a transmitting and receiving apparatus unit at the control office as indicated by a dotted line rectangle bearing the legend "C. T. C. office" in the drawing, and that this apparatus is connected by line wires to various field station units controlled by the office apparatus and located at spaced points along the trackway. Two of these units are indicated by dotted line rectangles in the drawing, and are identified by the legends "Station 5S" and "Station 7S", these units being located adjacent the left-hand and right-hand ends of the single track stretch. Each station unit is arranged to control one or more signal control relays such as the relays designated **R6HS** and **L8HS**, in accordance with different code signals transmitted from the office. To illustrate the present invention, it is deemed sufficient to point out that these stick relays may be located wherever de-

sired and that they may be individually picked up and released by the operator at the distant control office. These signal control relays therefore provide the means whereby the operator in the dispatcher's office may exercise his control over the local circuits and apparatus.

It is believed that the apparatus of my invention may be most readily understood from a description of its operation under various conditions of train movement, and starting with the apparatus in the condition shown in the drawing it will be assumed that signal RA6 is to be cleared for a movement from left to right through the stretch of single track. The signal control relays 10 R6HS and L8HS and the signal relays RA6H, RB6H, LA8H and LB8H are deenergized, so that all the signals are at stop, and assuming the stretch unoccupied, all of the track relays TR are energized, so that a line circuit is closed from 15 one terminal B of a suitable source of current at station 5S, back contacts 9, 10 and 11, of relays RB6H, RA6H and R6HS, front contacts 12, 13, 14 and 15 of the track relays 5TR, 4TR, 6TR and 7TR, line relay L8H and thence over the 20 common return wire 4 to the other terminal C of the same source of current. Relay L8H is energized over the circuit just traced so that a local circuit is completed from terminal B over back contacts 16 and 17 of relays LB8H and 25 LA8H, front contact 18 of relay L8H, back contact 19 of the traffic direction stick relay RFS, through the winding of the similar relay LFS, contact L of traffic lever F to terminal C. Relay LFS will therefore be energized and the corresponding 30 indication lamp LE will be lighted over a circuit including contact 20, to indicate that the established traffic direction is from right to left. Assume now that in accordance with the dispatcher's orders the local operator moves lever 35 F to the right. Relay LFS will release and complete a circuit from terminal B over contacts 16, 17, 18 and 21, relay RFS, contact R of lever F to terminal C, so that relay RFS will pick up, closing contact 22 to light lamp RE to indicate 40 that the established direction of traffic is from left to right. Relay RFS also closes its stick circuit which may be traced from terminal B over its own front contact 23 and winding, and over contact R of lever F to terminal C. It will be 45 apparent from a consideration of the circuits just traced that the established direction of traffic can not be changed by the local operator if one of the signal relays is energized to clear a signal governing traffic movements into the single track 50 stretch, or if any portion of this stretch is occupied so that a track relay is released.

The distant operator, acting under order from the dispatcher, may now clear signal RA6 or RB6, depending upon the position of switch 5, 55 by energizing the signal relay R6HS of the centralized traffic control system. When relay R6HS is energized by the distant operator, contact 11 will open to release relay L8H, and if relay RFS has been energized by the local operator, a circuit will be closed from one terminal B of a source of current at station 7S, front contact 38 of relay RFS, back contacts 24, 25 and 26 of relays LB8H, LA8H and L8HS, front contacts 27, 28, 60 29 and 30 of the track relays 7TR, 6TR, 4TR and 5TR, front contact 31 of relay R6HS, switch circuit controller contact 32 controlled by switch 5, and thence through the winding of the signal relay RA6H or RB6H and over line wire 4 to 65 terminal C of the same source, so that the signal

relay will become energized to clear the corresponding signal RA6 or RB6.

The local operator may now move his signal lever G8 to the right to clear signal R8 for the same direction, as indicated by a dotted line connection in the drawing. Signal RA6 or RB6 may be put to stop by the distant operator by releasing relay R6HS or by the local operator by moving lever F to the left, but neither operator can alone effect the clearing of a signal for the opposite 10 direction.

In order to clear signal LA8 or LB8, the local operator will move lever F to the left, and the distant operator will release relay R6HS, and if the stretch is unoccupied and all signals are at 15 stop, relays L8H and LFS will become energized as hereinbefore explained and the latter relay will complete its stick circuit including contact 20 33, similar to that for relay RFS already described. The local operator will also move signal lever G8 to the left, while the distant operator will effect the energization of relay L8HS, completing a circuit from terminal B, contact L of signal lever G8, front contacts 34, 35 and 36 of relays LFS, L8H and L8HS, circuit controller contact 25 37 controlled by switch 7, thence through the winding of relay LA8H or LB8H to terminal C to clear signal LA8 or LB8, depending upon the position of switch 7. It will be seen that the line relay L8H serves both as a signal relay for 30 controlling the signals for one direction and as a traffic relay for governing the reversal of traffic direction by the local operator.

The distant operator may now clear signal L6 for the same direction by the operation of a 35 stick relay, not shown, which is similar to relay L8HS but which is located at station 5S, or this signal may be controlled automatically, the control circuits for signal L6 not being shown as they form no part of the present invention. In 40 this case also it will be evident that signal LA8 or LB8 can be put to stop either by the distant operator or by the local operator, but that neither operator alone is able to restore the original direction of traffic and clear a signal leading into 45 the single stretch of traffic from the opposite direction.

It will be apparent from the foregoing that in part the traffic direction is controlled by the distant operator because in order to reverse traffic 50 he must deenergize one of the signal control relays R6HS and L8HS and energize the other, by means of the centralized traffic control system, but that this is without effect unless the local operator cooperates by operating his traffic lever 55 F to a corresponding position when conditions are proper. It will also be apparent that either operator may restore a cleared signal manually to stop at any time.

Although I have for simplicity shown each of 60 the signals as being of the two-position type, it is to be understood that in practice these will usually be controlled automatically to a third position in accordance with the condition of the next signal in advance for the same direction, 65 and further, that intermediate signals may also be employed and that these signals as well as the head block signals may be provided with directional control in accordance with the well known principles of absolute permissive block signaling.

In view of the foregoing description of the operation of the apparatus of my invention, it will be clear that the opposing signals leading into 70 the single track stretch are controlled by opera- 75

tors acting under orders from the dispatcher over two independent channels and if the dispatcher's orders as transmitted over either of these channels are improperly executed no dangerous situation will arise. One of these channels includes telephonic or other communication with the local operator who presumably is best informed as to local conditions affecting the admission of trains to the single track stretch, while the other channel is under the direct supervision of another operator, usually one stationed in the dispatcher's office, who is better informed than the local operator as to train movements in general, and in particular as to the locations and movements of trains at other points, and the safety of operation of trains is thereby enhanced.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a centralized traffic controlling system for railroads, a single track stretch, two signals including one at each end of the stretch for governing the movement of traffic in opposite directions into the stretch, a remotely controlled relay at each end of the stretch, a pair of directional relays including one for each direction, a manually controlled pickup circuit for each directional relay closed only when said stretch is unoccupied, a stick circuit for each directional relay including its own front contact and a back contact of the other directional relay, and control circuits for said signals controlled in accordance with traffic conditions in said stretch, each including a front contact of the remote controlled relay at the same end of the stretch and a front contact of the directional relay for the corresponding direction.

2. In combination with a stretch of railway track, two signals including one at each end of the stretch for governing the movement of traffic in opposite directions into said stretch, a line circuit for each direction each including a line

relay for controlling the signal for the corresponding direction in accordance with traffic conditions in said stretch, manually controllable traffic direction controlling means at one end of the stretch operable to reverse the traffic direction only when the adjacent line relay is energized and the signal it controls is at stop, and means manually controlled from a distant point for controlling said line circuits to clear one signal or the other in accordance with the condition of said traffic direction controlling means.

3. In combination with a stretch of railway track, two signals including one at each end of the stretch for governing the movement of traffic in opposite directions into said stretch, a line circuit for each direction each including a line relay for controlling the signal for the corresponding direction in accordance with traffic conditions in said stretch, two manually controllable relays at one end of the stretch independently controllable from different points, means effective only when both said manually operable relays are energized and the adjacent line relay is also energized for clearing the signal at the same end of the stretch, and means effective only when both said manually operable relays are deenergized for energizing the line relay at the opposite end of the stretch to clear the opposing signal.

4. In a centralized traffic controlling system for railroads, a stretch of railway track divided into track sections each provided with a track relay, a signal at each end of the stretch for governing the movement of traffic into the stretch, a line circuit for each signal each including contacts of each track relay, directional selecting means manually operable only when the line circuit for at least one of said signals is closed, signal control means operable from a remotely located control office for selectively clearing one signal or the other in accordance with the condition of said direction selecting means and of the line circuit for such signal, and means controlled by said direction selecting means for preventing a change in the condition of said direction selecting means when any portion of the stretch is occupied.

RONALD A. McCANN. 45
